(57) **CLAIM**

The ornamental design for a television receiver, as shown and described.

DESCRIPTION

FIG. 1 is a front perspective view of a television receiver, showing an example environment;

FIG. 2 is a front view of the television receiver of FIG. 1;
FIG. 3 is a rear view of the television receiver of FIG. 1;
FIG. 4 is a left-side view of the television receiver of FIG. 1;
FIG. 5 is a right-side view of the television receiver of FIG. 1;
FIG. 6 is a top plan view of the television receiver of FIG. 1;
FIG. 7 is a bottom plan view of the television receiver of FIG. 1;

FIG. 8 is an enlarged rear perspective view of the television receiver, without an example environment, showing vertical movement of the camera feature;

FIG. 9 is a second rear perspective view of the television receiver of FIG. 8, showing vertical movement of the camera feature;

FIG. 10 is a front perspective view of the television receiver of FIG. 1 that is included to more clearly depict the design as viewed from the front perspective view (a-a', b-b', c-c', d-d') of FIG. 1, without an example environment;

FIG. 11 is front view of the television receiver of FIG. 10;
FIG. 12 is a rear view of the television receiver of FIG. 10;
FIG. 13 is a left-side view of the television receiver of FIG. 10;

FIG. 14 is a right-side view of the television receiver of FIG. 10; and,

FIG. 15 is a top plan view of the television receiver of FIG. 10. The dash-dot-dot-broken line immediately adjacent the solid-line portions of the design represents an unclaimed boundary of the design. The remainder of features shown in broken lines in FIGS. 1, 2, 3, 4, 5, 6, and 7, form no part of the claimed design.
